UNITED STATES PATENT OFFICE.

ALFRED G. F. KUROWSKI, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,177,874.

Specification of Letters Patent.

Patented Apr. 4, 1916.

Application filed April 28, 1913. Serial No. 763,979

To all whom it may concern:

Be it known that I, ALFRED G. F. KUROWSKI, a citizen of the United States, residing in Brooklyn, in the county of Kings, city and State of New York, have invented certain new and useful Improvements in Type-Writing Machines, of which the following is a specification.

The present invention relates to a type-writing machine with which is combined tabulating mechanism comprising a series of column stops on the carriage adapted to be selectively projected into position to be intercepted by counter-stops on the machine frame.

An object of the invention is to provide means actuated by the same key to selectively project the stops on the carriage and also restore the stops to inactive position.

A further object is to provide an improved form of restoring cam which will effect a successive return of the projected stops and thereby reduce the duty placed on the cam-operating mechanism and secure a smooth and easy action of said mechanism.

The counter-stops may consist of a series of denominational stops for a decimal tabulating system, the stops being preferably in the form of vertical bars slidable vertically in a stationary casing and adapted to be selectively actuated by a bank of tabulating keys to project the denominational stops into the path of a projected column stop on the carriage. The column stops are arranged in a row extending in the line of the carriage travel, and are adapted to be selectively projected or lowered into the path of the operated counter-stops. The column stops are yieldingly held in operated position and are restored by a key-actuated cam adapted to be swung forward into position to lift the stops either as the cam is swung forward or during the return of the carriage while the cam is in said forward position. The same key is utilized when depressed to project the column stops and when lifted above its normal position to actuate said restoring cam.

Other objects and advantages will herein-after appear.

In the accompanying drawings, Figure 1 is a sectional elevation view of an Underwood typewriting machine with my invention applied thereto. Figs. 2 and 3 are re-

spectively a plan and a front elevation view of the restoring cam. Figs. 4, 5, and 6 are 55 sectional elevation views of the same, as indicated by the lines 4—4, 5—5 and 6—6 respectively on Fig. 2. Fig. 7 is a perspective view of the tabulating mechanism. Fig. 8 is a sectional elevation view showing the 60 column stop-projecting key depressed and a column stop projected. Fig. 9 is a similar view showing the key lifted above normal position, and the restoring cam in operative position.

The type keys 1 on the key levers 2 operate through the bell cranks 3 to swing the type bars 4 about their fulcrum 5 and bring the types 6 up to the printing point of the platen 7, which is mounted in the carriage 8, adapted to be operated as usual in the letter-feed direction by means of a spring barrel. The type bars when moved to printing position actuate a universal bar 9 and thereby operate escapement dogs 10 co-operating with an escapement wheel 11 which is connected to rotate with a pinion 12 in mesh with a rack 13 on a frame 14 pivoted at 15 to the carriage.

The tabulating mechanism comprises a 80 bank of keys 16 on the forward ends of levers 17, pivoted intermediate their ends on a fulcrum rod 18 and at their rearward ends supporting vertical rods forming a series of denominational stops 19. These rods are supported and guided in a frame 20 having a top plate 21 with a series of slots or openings 22 at letter-space distances apart, through which the stops are adapted to be projected. The stops are normally supported with their upper ends substantially flush with the upper surface of the plate 21. When a key is depressed the corresponding stop 19 is projected into a position to intercept any projected stop of a series of column 95 stops 23, the stops 19 thus forming counter-stops for the column stops 23.

The column stops 23 are supported in a frame 24 connected to the carriage and comprising parallel rack bars 25 in which the 100 stops 23 are vertically supported and guided. Each stop 23 is provided in its lateral edges with notches 26 forming seats for spring-actuated detents 27 whereby the stops are yieldingly held in a normal elevated position, shown in Fig. 7, in which the lower

ends of the stops are flush with the lower surface of the frame 24, or in their projected position, as shown in Fig. 8. The construction of the stops and their supporting frame may be the same as that disclosed in my copending application, Serial Number 722,582, filed September 27, 1912. The column stops are adapted to be projected by means of the vertically-disposed arm or projecting device 28, which extends upward through an opening 29 in the plate 21 and has its upper end extended rearward to a position over the stops. The lower end of the arm 28 is connected by a pivot 30 to a rock arm 31 secured to a shaft 32. The latter is actuated by a key lever 33 having a fulcrum 34 and connected through a link 35 to a second rock arm 36 on the shaft 32.

During the travel of the carriage the stops 23 are successively brought into position directly beneath the arm 28, said stops being each a letter-space distance in advance of the preceding stop. When the key 37 on the lever 33 is depressed the shaft 32 is rocked and the arm 28 moved downward, carrying with it a stop 23 to the position shown in Fig. 8. The stop is held in this projected position by the detent 27, while the lever 33 and connected parts are restored to normal position by means of a spring 38 when the key is released.

The column stops 23 are restored to inoperative position by means of a restoring cam 39 normally supported in rear of the stops 35 and adapted to be moved forward to operative position by means of links 40 connecting the cam with the vertically-disposed rock arms 41 secured to a rock shaft 42. The latter has secured thereto an arm 43, in 40 the forked end 44 of which rests in an arm or projection 45 of the lever 33. A coil spring 46 normally holds the cam in its rearward or inoperative position, with the arm 41 resting against a stop 47. When the key 37 45 is lifted from its normal position (Fig. 1) to the position shown in Fig. 9, the projection 45 operates through the arm 43 to rock the shaft 42 and swing the arms 41 and with them the cam 39 forward to a position beneath the column stops 23. By reference to Figs. 2 to 6, it will be seen that the cam 39 is somewhat irregular in shape, the central portion being higher than the end portions, its forward ends also having a curved outline comprising a central projecting portion 48. The purpose of this conformation is to permit a successive actuation of the stops by the cam as the latter moves forward, rather than operating a number of stops at once, and also a gradual lifting of each stop. The power required to restore the stops is thus materially reduced and a much smoother and easier action of the restoring key is obtained. As the cam moves 60 forward all of the projected column stops 65

that may lie in its path are restored or partially restored to inoperative position, and the restoration of the stops is completed by the travel of the carriage, which brings all the stops in succession into position to be 70 fully restored by the cam.

The movement of the arm 28 is limited in both directions by a pin 49 extending through a slot 50 in said arm. The normal position of the lever 33 is determined by 75 the projection 45 bearing against the arm 43, the spring 38 being too weak to overcome the spring 46 and swing the cam forward.

When a tabulator key is depressed the corresponding stop 19 is projected into the 80 path of any projected column stop or stops 23, and at the same time the carriage is released from the escapement mechanism and permitted to run forward until arrested by the engagement of a column stop 23 with a 85 projected counter-stop 19. The carriage is released by the following means. Each counter-stop 19 is formed with a shoulder 51 on which rests a universal bar 52 connected to a rock shaft 53. An arm 54 on the 90 rock shaft is connected through a link 55 to a lever 56 pivoted at 57, and carrying at its forward end a roller or wheel 58 on which the carriage rack bar 13 runs. When any tabulator key is depressed and a counter- 95 stop projected, the universal bar 52 is lifted and through the link 55 operates the lever 56 to lift the carriage rack 13 out of mesh with the pinion 12, so that the carriage is free to move forward until arrested by the 100 counter-stop.

Variations may be resorted to within the scope of the invention, and portions of the improvements may be used without others.

Having thus described my invention, I 105 claim:

1. In a typewriting machine, the combination of a carriage, a row of vertically movable stops on the carriage, said row extending in the direction of the carriage 110 travel, a projecting device operable to selectively project said stops vertically downward, a restoring cam movable forwardly and rearwardly into and out of a position beneath the stops in which it cooperates with 115 the carriage to restore the stops as they are moved by the carriage against the restoring cam, and a key connected to operate one of said devices when moved in one direction from normal position and to operate the 120 other of said devices when moved in the opposite direction from normal position.

2. In a typewriting machine, the combination with a carriage, of a horizontal row of vertically-disposed stops thereon, means 125 for selectively projecting said stops downward, a cam movable bodily forward into stop-restoring position beneath said stops, said cam being formed to effect successive and gradual restoration of the stops during 130

the carriage travel, means to operate said cam, and counter-stops for the carriage stops.

3. In a typewriting machine, the combination with a traveling carriage, of stops thereon, a stop-projecting device extending over the said stops, a key, connections from said key to the stop-projecting device, a rock shaft, vertically-disposed arms thereon, a restoring cam connected to said arms, and means operated by said key to rock said shaft and move the restoring cam into position to restore the carriage stops.

4. In a typewriting machine, the combination with a carriage, of a series of stops thereon, a counter-stop, a key, means actuated thereby when the key is moved in one direction to selectively project the stops into position to be intercepted by the counter-stop, and additional means actuated by said key when moved in the opposite direction and cooperating with the carriage to restore the stops to ineffective position on the carriage as the stops are brought by the travel of the carriage into engagement with the restoring means.

5. In a typewriting machine, the combination of a key, a stop-projecting device actuated by said key when the latter is moved in one direction from its normal position of rest, a stop carrier, stops thereon, said carrier movable to bring the stops selectively into position to be projected by said device, and a stop-restoring device moved by said key to stop-restoring position when the key is moved in the opposite direction from its normal position of rest, the stops being moved by the carrier against the stop-restoring device and thereby moved on the carrier to restored position.

6. In a typewriting machine, the combination with a set of stops and a counter-stop, of a key, means actuated by the key when moved in one direction from a normal position of rest, to selectively set the stops into operative position for cooperation with the counter-stop, and stop-restoring means actuated by the key when the latter is moved in the opposite direction from said normal position, said set of stops movable relatively to the stop-restoring means, to bring the stops successively into engagement with said restoring means and thereby cause the stops to be restored.

55 7. In a typewriting machine, the combination with a set of stops and a counter-stop, of a stop-projecting device to selectively project the stops into operative position for cooperation with the counter-stop, a stop-restoring device, a key, operative connections between the key and the stop-projecting device for actuating the latter when the key is moved in one direction from its normal inactive position, connections from the key to the stop-restoring device for mov-

ing the latter to operative position when the key is moved in the opposite direction from said inactive position, and means for moving the set of stops to bring the individual stops successively into engagement with the stop-restoring device while the latter is held in operative position, and thereby cause the stops to be restored.

8. In a typewriting machine, the combination with a set of stops and a counter-stop, of a stop-projecting device to selectively project the stops into operative position for cooperation with the counter-stop, a stop-restoring device, a key, operative connections between the key and the stop-projecting device for actuating the latter when the key is moved in one direction from its normal inactive position, connections from the key to the stop-restoring device for moving the latter to operative position when the key is moved in the opposite direction from said inactive position, means for moving the set of stops to bring the individual stops successively into engagement with the stop-restoring device while the latter is held in operative position, and thereby cause the stops to be restored, and means to automatically return said devices to inoperative position when the key is released, after being operated in either direction.

9. In a typewriting machine, the combination with stops, of a counter-stop, a stop carrier supporting the stops in an ineffective position, a stop-projecting device, a stop-restoring device, an actuating key, and connections from the key to said devices for actuating the projecting device, and selectively projecting the stops into position to be engaged by the counter-stop when the key is depressed below normal position and for actuating the restoring device to operative position when the key is lifted above normal position, said stop carrier movable relatively to the restoring device to bring the projected stops successively into engagement with the restoring device and thereby restore the stops.

10. In a typewriting machine, the combination of a set of stops, a counter-stop, a key having a normally inoperative position, means operated by the key for selectively projecting the stops into position to be intercepted by the counter-stop when the key is actuated in one direction from said inoperative position, a stop-restoring device set to operative position by said key when the key is actuated in a different direction from said inoperative position, and means cooperating with the stop-restoring device to restore the stops by a relative movement of the set of stops and the stop-restoring device while the latter is retained in said operative position.

11. In a typewriting machine, the combination with a carriage, of a stop carrier

thereon, a series of stops on said carrier, a stop-projecting device to selectively project the stops to an operative position on the carrier, a key movable in one direction from a normally inactive position to actuate said device, and a stop-restoring device operated by the key when the latter is moved in the opposite direction from said inactive position, the stop-restoring device coöperating with the carriage to restore all the projected stops by a single operation of the key.

12. In a typewriting machine, the combination with a carriage, of a stop rack on the carriage, a row of vertically-movable stops on said rack, a stop-projecting device to project the stops to an operative position on the rack, a restoring device movable into position to restore the projected stops during the travel of the carriage, and a key movable in one direction from normal position for actuating one of said devices and movable in the opposite direction from normal position for actuating the other of said devices.

13. In a typewriting machine, the combination with a carriage, of stops thereon, counter-stops, said stops settable into position to be intercepted by the counter-stops, and a restoring cam movable into a stop-restoring position for restoring the said stops, said cam formed to successively engage and successively restore the stops in its path as it is moved to said position, and to restore the remaining set stops as they are moved over the cam by the travel of the carriage.

14. In a typewriting machine, the combination with a carriage, of a series of stops thereon, counter-stops, means to project said stops into position to be intercepted by the counter-stops, and a restoring cam movable into a position between said stops and counter-stops for restoring the said stops, said cam formed to successively engage and successively restore the stops in its path as it is moved to said position.

15. In a typewriting machine, the combination with a carriage, of a series of stops thereon, counter-stops, means to project said stops into position to be intercepted by the counter-stops, a restoring cam movable into a position between said stops and counter-stops for restoring the said stops, said cam formed to successively restore the stops in its path as it is moved to said position, and a key connected to operate said stop-projecting means and said restoring cam.

16. In a typewriting machine, the combination with a carriage and a series of stops thereon projectable to an operative position, of counter-stops, a casing in which said counter-stops are mounted for vertical movement into the path of the projected stops, a swinging frame comprising arms on

opposite sides of said casing and a stop-restoring cam connecting said arms, a key to swing said frame and move the restoring cam into a position between the stops and counter-stops for restoring said stops, and a key to operate said swinging frame.

17. In a typewriting machine, the combination with a carriage and a series of stops thereon projectable to an operative position, of counter-stops, a casing in which said counter-stops are mounted for vertical movement into the path of the projected stops, a swinging frame comprising arms on opposite sides of said casing and a stop-restoring cam connecting said arms, a key to swing said frame and move the restoring cam into a position between the stops and counter-stops for restoring said stops, and a stop-projecting device extending over said stops, the latter being selectively brought by the movement of the carriage into a position beneath said stop-projecting device to be actuated thereby, said key connected to operate said stop-projecting device.

18. In a typewriting machine, the combination with a carriage, of a rack thereon, a series of stops carried by said rack, a counter-stop, said stops projectable into position to be intercepted by the counter-stop, a stop-restoring cam, and means to swing said cam into a stop-restoring position, said cam formed to successively restore the stops lying in its path as it is moved to said restoring position and also formed to successively restore the remaining projected stops when the carriage is moved while the cam is in said restoring position.

19. In a typewriting machine, the combination with a carriage and a rack thereon, of stops on said rack, a counter-stop, said stops projectable downwardly into position to coöperate with the counter-stop, a swinging frame comprising a stop-restoring cam, said cam normally lying behind said stops, and a key to swing said frame and move said cam forward beneath said stops and cam the stops to a non-projected position.

20. In a typewriting machine, the combination with a carriage, of a rack bar thereon, a series of stops on said rack bar, said stops projectable downwardly to an operative position, a coöoperating counter-stop, a stop-setting arm having a projection overhanging said stops, a key for moving said arm downwardly and thereby project the stops lying beneath said projection, and a stop-restoring cam mounted to swing transversely of the direction of the carriage travel into a position beneath the stops, said cam operable by the stop-projecting key.

21. In a typewriting machine, the combination with a carriage, of a series of stops thereon, a counter-stop, a key, means actuated thereby to selectively project the stops into position to be intercepted by the

counter-stop, and a stop-restoring device moved by said key into a position between the projected stops and the counter-stop to restore the stops to ineffective position on the carriage.

22. In a typewriting machine, the combination of a key, a stop-projecting device actuated by said key when the latter is moved in one direction, a stop carrier, stops thereon movable into and out of projected position on the carrier, said carrier movable to bring the stops selectively into position to be projected by said device, and a stop-restoring cam movable by said key into the path of a projected stop when the key is moved in the opposite direction, said movement of the cam being transverse to the movement of the stop on the carrier, the cam being operable by said movement to cam the stop to restored position.

23. In a typewriting machine, the combination of stops, a counter-stop, a key, means actuated by the key when moved in one direction to selectively set the stops into position to be engaged by the counter-stop, and a stop-restoring cam actuated by the key when moved in the opposite direction into position to hold the counter-stop inoperative and restore the stops.

30 24. In a typewriting machine, the combination with a stop carrier, of stops thereon, a counter-stop, a stop-projecting device, said carrier movable to bring the stops selectively into operative relation to the stop-projecting device, said device operable to project the selected stop into position to be engaged by the counter-stop, a stop-restoring device, a key, and operative connections between the key and said devices operable while a stop is in said operative relation to the stop-projecting device to both project and restore the stop by the actuation of said key.

25. In a typewriting machine, the combination of stops, a counter-stop, a key having a normally inoperative position, means for selectively bringing the stops into operative relation to the said key, and means for projecting the selected stop into position to be intercepted by the counter-stop and restoring said stop respectively when the key is actuated in different directions from said position while the stop is in said relation to the key.

26. In a typewriting machine, the combination with a carriage, of a stop rack on the carriage, a row of vertically-movable stops on said rack, counter-stops movable into the path of said stops, a stop-projecting device to project the stops to an operative position on the rack, a restoring device movable into a position to restore the projected stops during the travel of the carriage, said restoring device overlying the counter-stops when in stop restoring position and thereby preventing the counter-stops from being moved to operative position, and a key for said projecting and restoring devices.

27. In a typewriting machine, the combination with a carriage, of a set of tabulator stops, a support for said stops, a stop-projecting device mounted on the machine frame for projecting said stops, a key operable when moved to one position to actuate said stop-projecting device, the stops being successively brought, during the travel of the carriage, into position to be engaged by said stop-projecting device, whereby the stops may be selectively projected, and means operated by said key, when moved to another position, to return the stops.
